Dennis Gabor, London, England, assignor to National Research Development Corporation, London, England, a corporation of Great Britain

Application June 18, 1956, Serial No. 592,142

Claims priority, application Great Britain June 20, 1955

14 Claims. (Cl. 313—77)

This is a continuation-in-part of application Serial No. 309,677, filed on 15th September, 1952, now abandoned, and application Serial No. 549,712, filed on November 29, 1955, now Patent No. 2,795,729, issued June 11, 1957. These applications describe and illustrate various forms of cathode ray tube having the feature that they can be made flat in shape, that is to say, without any appreciable depth perpendicular to the screen, the conical and tubular neck portions of conventional cathode ray tubes being dispensed with.

In one form of such a cathode ray tube, the structure is housed in an envelope the shape of which may be regarded as resembling that of a hand mirror. In a preferred arrangement, however, a more compact structure is achieved by doubling the electron beam back upon itself by means of an electron lens adapted to receive a beam deflectable in one plane and deliver it back in another plane parallel to the first but displaced therefrom.

One object of the invention is to provide an electron lens adapted to effect such a reversal of an electron beam.

Another object of the invention is to provide a reversing lens for use in a flat cathode ray tube as above described, which will enable the deflection angle, through which the beam must be deflected for producing a television line scan in a cathode ray tube of the kind above described, to be materially reduced.

A further object of the invention is to provide a reversing lens for the purpose of reversing upon itself a cathode ray beam deflectable in a given plane, which will enable certain aberrations, due to such deflection of the electron beam, to be reduced or eliminated.

Yet another objection of the invention is to provide a cathode ray tube which will be compact and not greatly exceed in any of its dimensions the dimension of the picture screen.

Further objects will appear as the description proceeds.

In the cathode ray tubes described in my prior application Serial No. 549,712 the picture producing electron beam is first deflected in one direction only, parallel to the screen surface, and then proceeds in a direction which is also substantially parallel to the screen, at a relatively small distance from its surface. When the beam reaches a certain zone, it is strongly deflected towards the screen by a locally applied electric field, so that it forms a curved pointer, meeting the screen at the desired point. This localized electric field extends over a substantially linear zone which always intercepts the beam, irrespective of its first mentioned deflection, and is shaped in such a way that the beam is focused by said field at the same time as it is deflected thereby. In the application of the invention to television, the linear zone of the electric field is in the direction of the line scan, while the frame scanning is achieved by moving said field parallel to itself, in the direction of the frame scan. It follows that, as the beam moves substantially parallel to the screen and close to it, the tube can be made very flat. No "throw" at right angles to the screen is required, as in all conventional cathode ray and television tubes.

The functional principle of the tube described in that prior application may be translated into structural terms in the following manner. Within a glass envelope there is provided a substantially plane fluorescent picture

5 screen adapted to be maintained at a maximum positive potential of the order 5-15 kv. An array of linear conductors is arranged in a plane parallel to the screen, the conductors being substantially parallel to one another and to the direction of the line scan, insulated from one another and preferably associated with a common capacitive backing plate. This array of conductors may be called the scanning array. An electron gun is positioned in the envelope and arranged so as to project an electron beam into the space between the scanning array and the screen. If the array is charged up to a maximum positive potential, equal to the potential of the fluorescent screen, there is no electric field between said array and the screen, and the cathode ray beam will pass through between them without being deflected. If, however, a zone of the array

10 is discharged, so that in the zone successive conductors assume a graduated range of potentials extending from the maximum positive potential down to a potential in the neighborhood of that of the cathode of the electron gun, the electrons will be repelled by said zone and thrown

15 towards the fluorescent screen. If the conductors of the array are discharged, one by one, progressively across the array in the direction towards the electron gun, the zone will travel across the array so that the beam will be thrown on the screen after a progressively diminishing

20 length of travel, and this effect may be used to provide the frame scan for a television picture presentation employing the tube.

The discharging of the conductors to effect the frame scan may be achieved in any suitable manner as by a special organ, called the scanning valve, contained in the vacuum space of the tube itself. The scanning valve, which forms no part of the present invention, is described and illustrated in my application Serial No. 549,712 filed November 29, 1955.

25 In one form of the device the electron beam is directed into the space between the screen and the array of conductors which perform the forward deflection from an electron gun positioned below the screen, and the whole is enclosed in an envelope which is of a shape referred to above as resembling that of a hand mirror. In

30 the more compact arrangement which has also been referred to, however, the gun is placed behind the array of conductors and is projected downwardly, and is then turned back upon itself around the bottom edge of the array of conductors so as to enter in an upwards direction

35 the space between the conductors and the screen. For this purpose an electron lens according to the present invention is used. The lens has a trough-shaped repeller electrode normally maintained at low potential (e.g. the cathode potential of the electron gun), a central or spine electrode maintained at high positive potential, and two side or flanking electrodes also maintained at high positive potential.

40 The electron beam enters between the spine electrode and one of the flanking electrodes, is bent round the edge of the spine electrode back upon itself, emerging between the spine and the other flanking electrode. The lens may be regarded as a cylindrical lens

45 having a U-shaped optical axis.

45 The invention will be better understood from the following description given with reference to the accompanying drawings in which:

50 Figures 1, 2, 3 and 4 are a front view, a side view, a rear view and a plan view, respectively, all partly sectioned and somewhat diagrammatic in character, of one form of cathode ray tube embodying the invention.

55 Figure 5 is an enlarged vertical section through the electron lens used in the tube illustrated in Figures 1-4.

Figure 6 is a cross section of a modified reversing lens according to the invention.

Figures 7 and 8 are an elevation, partially broken away and an elevational cross section, respectively, of a curved reversing lens according to the invention, in association with a pair of deflector electrodes.

Figure 9 is a perspective view of a deflection system for use in conjunction with a reversing lens according to this invention.

Figure 10 is a perspective view of a modified spine electrode for a lens according to the invention, and

Figure 11 is a perspective view of a modified repeller electrode for a lens according to the invention.

In Figures 1-4 the vacuum envelope 1 consists of glass on the side from which the screen 2 is viewed, while the other parts may be made of glass or metal. The fluorescent screen 2 is in the form of a phosphor coating on a sheet of suitable material such as glass, or glass cloth suitably tensioned, and may be backed with the now widely used metallic layer. Facing the screen, and at a relatively small distance from it, is arranged the scanning array 3, details of which are given in my application Serial No. 549,712 filed November 29, 1955. The array is backed, at least in part, by the metal plate 4, which may be used as support for the rear array but is insulated therefrom and constitutes the common capacitive backing of the array. As described in the aforesaid application, the conductors of the array 3 may be folded over in a loop 5 to form front and rear arrays, and also folded around the backing plate 4 and into a loop 6 which forms the outer electrode of the scanning valve, whose grid 7 and collecting electrode 8 are also shown. The scanning valve forms no part of the present invention and need not therefore be described in detail here.

The electron beam E is formed by the electron gun 9, which may be of conventional design, and is not therefore shown in detail.

The gun 9 is placed behind the scanning array 3 and positioned in the vertical plane of symmetry perpendicular to the screen and pointing vertically downwards. At the bottom of the tube the beam from gun 9 is reversed upon itself so as to pass upwards between the array 3 and screen 2, the reversal of the direction of the beam being effected by means of an electron lens formed of elements 13, 14 and 15 to be described in more detail later.

The line scan, that is to say the deflection horizontally across the fluorescent screen as shown in Figure 1, is effected by electrostatic deflection plates 16, 16.

Two pairs of small deflector electrodes 11 and 12 are provided which operate in opposition to one another so as to displace the beam parallel to itself. For a tube operating only in black and white these electrodes are given fixed potentials adjusted to direct the electron beam exactly into the narrow gap between the screen 2 and the array 3, thus correcting for small inaccuracies in the mounting of the electron gun relative to said gap. In color tubes they have the additional function of color control.

It is known that electrostatic deflection is rather unsuitable for wide scanning angles, but in view of the long "throw" of the beam achieved by bending it back upon itself, the scanning angle can be reduced to a low value; $\pm 19^\circ$ in the example illustrated. It can be still further reduced by adopting a modified form of reversing lens to be described later.

As shown in Figures 1 and 3, the effect of the electron lens 13, 14, 15, viewed in the plane of these drawings, is the same as specular reflection on a line M—M, which is well outside the physical boundaries of the lens. Thus the deflectors 16 must be so adjusted as to scan the mirror image of the fluorescent screen relative to said line M—M, as illustrated in Figure 3. It will be clear that trapezium correction must be applied to the scan, and a corresponding correction applied to the focus, at least

in the plane of Figures 1 and 3. Such techniques have been employed in the operation of previously known cathode ray tubes in which the screen is inclined relative to the tube axis. On the other hand, no "keystone correction" need be applied in the present case because the line in which the electron beam meets the screen is substantially predetermined by the deflecting zone, set up by the deflection array, which is straight.

This type of tube is eminently suitable for manufacture, because the fluorescent screen, the scanning array, the backing plate, the gun and deflector system and the electron lens or mirror may be fixed relative to one another by suitable beams, struts and spacers, well known in the art of electron tube manufacture, so as to form one composite structure. The envelope 1 is preferably made of two dish-shaped halves, divided in the symmetry plane S—S as shown in Figures 2 and 4, and the composite structure above referred to is sealed between them, preferably supported by studs which project between the two half-dishes, in pre-moulded grooves, not shown in the drawings. The electrode leads are also preferably sealed in at the joint between the two halves. Thus great accuracy of manufacture can be achieved, because the internal structure can be completely assembled in jigs, and the relative positions of the parts are not affected by the subsequent glass sealing operations. The most critical adjustments are those which affect the parallelism of the beam and the fluorescent screen. These, however, can be made after the tube is completed. If the plane in which the beam is scanned for the line scan happens to be tilted around a horizontal axis, so that it runs at an angle instead of parallel to the screen, the bias of the trimming deflectors 11 or 12 may be slightly altered to correct it. If this plane is twisted round a vertical axis, e.g. by imperfect positioning of the deflectors 16, the twist can be compensated by a weak vertical magnetic field, produced by a few turns of a current-carrying wire wound round the tube, say at the level of the electrodes 13. The electron lens or mirror 13, 14, 15 is shown in one form in detail in Figure 5. In the form illustrated in this figure the lens comprises two cylindrical electrodes 13, 13 hereinafter called flanking electrodes placed one on each side of a third electrode 14, which will be called the spine, also cylindrical, located in the symmetry plane S—S. All three of these electrodes are connected to a positive potential, preferably the highest positive potential in the tube, V_m . Associated with electrodes 13, 13 and 14 is a hollow cylindrical electrode or trough 15 termed the repeller electrode, which is positioned symmetrically beneath the other electrodes and is kept at or near the potential of the cathode of the picture beam electron gun 9. These electrodes are so designed that the electric field between them brings a parallel electron beam to a focus in the symmetry plane, and the emerging beam is again collimated. The system is best regarded, therefore, as an electron lens system with a curved optical axis.

Figure 5 shows the equipotential lines, numbered in terms of V/V_m , where V_m is the potential applied to electrodes 13, 13 and 14, and the potential of electrode 15 is assumed to be zero, i.e. the potential of the gun cathode. The figure shows also three electron trajectories. It is evident by inspection that if the incoming, collimated beam is focused in the symmetry plane, the outgoing beam will be again collimated and parallel to the original direction. A more accurate analysis reveals that in order to obtain the result it is not necessary to focus a wide beam exactly in one point of the symmetry plane. It is found that it is sufficient if the focus of that thin bundle of trajectories which meets the symmetry plane at right angles is focussed in the said plane. The central trajectory of this thin bundle is the optical axis. It is found that trajectories which enter the lens at some larger distance from the optical axis will meet the symmetry plane a little above its intersection with the optical axis, and at an incidence angle, relative to the normal, which may

be positive or negative. In first approximation the small height difference will be a quadratic function of the incidence angle. This, however, means that in this region a ray which meets the symmetry plane at a height h , at incidence angle $+\alpha$, will continue at the other side as the ray which has the incidence angle $-\alpha$ and will also emerge parallel to the symmetry plane. In other words, the present system, by its symmetry properties, has no "second order error" and therefore retains its property illustrated in Figure 5 for quite wide beams.

Another valuable property is that a beam which is not collimated will emerge from the system with the same angle of convergence or divergence as that with which it entered. This follows from the fact that the system as shown in Figure 5 is what is known in optics as a "telescopic system." Finally, thanks to the near optimum properties of the electric field shown in detail in Figure 5, a slight departure from the correct shape is of little consequence, and can be corrected by a small D.C. bias, applied to the electrode 15.

Strictly speaking, a cylindrical system will retain the properties described only for electron trajectories which are nearly parallel to the plane of the drawing in Figure 5. Electrons of an energy corresponding to V_m , which have been deflected by the line deflector system 16, 16 (see Figures 12-15) at some angle α relative to the plane of the paper, will behave as if they had only the energy $V_m \cos^2 \alpha$ in that plane. They will be over-focused and will emerge as a somewhat diverging bundle. This effect can be completely avoided if a voltage $V_m \sin^2 \alpha$ is applied to the electrode 15, so that the voltage drop in the lens is $V_m (1 - \sin^2 \alpha) = V_m \cos^2 \alpha$. This correcting voltage may be obtained, by means well known in themselves, by squaring the voltage applied between the line deflectors 16, 16.

An alternative method of correction is to depart slightly from exact cylindricality of the electrode system, preferably by bending the central electrode 14 somewhat, so that its distance from 15 is a little larger at the ends than in the middle of the mirror system.

The performance of the lens according to the invention can be improved for some purposes and particularly for use in a television cathode ray tube such as that described above with reference to Figures 1 to 4, by modifying the design in accordance with the principles now to be described with reference to Figures 6 to 11 of the accompanying drawings. The lens described with reference to Figures 1 to 5 acts as a plane mirror in the line MM of Figure 3 so far as concerns the path of the beam in planes parallel to the plane of the cathode ray tube screen. The deflection sensitivity of the system comprising the lens in combination with deflection plates 16 can, however, be improved and certain aberrations of the system removed if the lens is made curved so as to behave as a convex mirror considered in planes parallel to the cathode ray tube screen.

In Fig. 6 the three electrodes 13, 14 and 15 correspond to the elements similarly numbered in the previous figures. 15 is a trough-shaped repeller electrode, connected to the cathode of the tube in which the device is used, while the inner electrode or "spine" 14 and the outer or flanking electrodes 13 are connected to the most positive electrode in the tube.

As explained above a cylindrical lens of this kind has a curved optic axis, which in the cross section of Fig. 6 appears as that ray, shown dot-dashed, which enters and leaves the lens parallel to its symmetry line at equal distances therefrom. This may be called the "telescopic" property of the lens. It has also been shown above that this curved line is, by reason of the symmetrical design of the lens, an optic axis in the same sense as the straight axis of an ordinary cylindrical lens. Rays entering the reversing lens parallel to the symmetry line, a little off the optic axis, will not intersect the vertical symmetry line in exactly the same point as does the optic axis, but

a little higher, but in first approximation this point will be the same for two rays which are at the same small distance, right and left, from the optic axis. Consequently the second order error is zero for this lens for thin beams centered on the optic axis, and if they were originally parallel beams, they will leave the reversing lens again as parallel beams. More generally, all errors of even order vanish by reason of the symmetrical design. There remain, the errors of odd order, the first of which, the third-order error is usually referred to as the cylindrical aberration but this too can be reduced or eliminated. It may be noted that the telescopic property of the lens applies not only to beams which enter the lens parallel to the symmetry plane, but also to those at small angles thereto. In the following discussion the relative dimensions of lenses according to this part of the invention will be referred to in the following terms:

The distance A between the two branches of the optic axis is taken as unity, and all other dimensions are referred to this.

W =The total outer width.

W_1 =The width of the repeller of "negative trough" 15.

W_2 =The width between the outer positive electrodes 13.

H =The height of the repeller.

25 G_1 =The gap between the repeller 15 bottom and edge of the central electrode or spine 14.

G_2 =The gap between the repeller and the outer electrodes.

30 w =The thickness of the centre electrode or "spine."

r_1 =Curvature radius of the repeller, at the bottom.

r_2 =Curvature radius of the repeller, at the rim.

r_3 =Curvature radius of the flanking electrodes, at the rim.

35 R_1 =Radius of curvature of repeller bottom.

R_2 =Radius of curvature of spine edge.

R_3 =Radius of curvature of repeller edge.

R_4 =Radius of curvature of positive flanking electrodes.

Z =Distance of deflection centre from repeller bottom.

40 z =Distance of reversing line from repeller bottom.

All these dimensions are marked on the drawings.

Beams filling up to one-half of the free entrance and exit cross sections can be handled. Beyond this errors of 5th and higher order make their appearance.

45 By the telescopic property of the reversing lens, it will handle not only parallel but diverging or converging beams, without altering the convergence angle. If the entering beam converges in a point x units below the level I'-I" it will emerge so as to converge x units above it, with unchanged convergence angle. The line I'-I" is the locus of the intersections of incident and emergent rays and will be referred to below.

In the lens according to this aspect of the invention, the electrodes are curved parallel to the plane in which 55 the electron beam is to be deflected and the effect on the operation of the lens introduced by a convex curvature is illustrated in Fig. 7. In this figure and in Fig. 8 the deflector plates by which the beam is deflected have been given the same reference number, 16, as before.

60 As Figs. 7 and 8 show, the reversing lens acts in the XY-plane roughly speaking like a convex mirror. Though the initial and the final rays, of which three are shown, intersect on a line I'-I" which theory and experiments have shown to be almost straight, at a distance z

65 below the bottom of the repeller, the angles are nevertheless much magnified, because the two rays will form very nearly equal angles with a line O'-O" at right angles to the bottom of the repeller trough. Consequently the angles α_2 are larger than the corresponding angles α_1 , in 70 the case shown about 3.3 times. Thus, with the same distance Z of the deflection centre from the repeller, a sweep angle of e.g. $\pm 13^\circ$ is sufficient to cover a screen which with a straight reversing lens might require $\pm 30^\circ$ or more.

75 This reduction of the primary deflection angles α_1 has

some important practical consequences. The first is an increase in deflection sensitivity, that is to say a reduction in the scanning voltage required for the horizontal sweep. This reduction is larger than expressed by the ratio of e.g. $13/30=0.43$, because the sweep voltage increases more than linearly, almost quadratically, with the maximum deflection angle, owing to the fact that at larger angles the deflecting plates 16 must be spaced wider apart.

An even more important consequence is the reduction of the aberration known as deflection focusing or deflection astigmatism, that is to say the focusing of rays in the X-direction. It is known that, other things being equal, this error increases with the square of the deflection angle, and is inversely proportional to the length of the deflector plates. By employing the device of the present invention there is no need to use very long plates 16. With deflecting plates of the shape as used in conventional cathode ray tubes the peak-to-peak scanning voltage for $\pm 13^\circ$ deflection is only about one tenth of the beam voltage. Other things being equal therefore, the deflection aberration is decreased in the ratio of e.g. $13/30^2=0.19$. A third consequence is that even the small remaining aberration may be partly corrected by the curved reversing lens, and can be entirely corrected or even over-corrected if desired, so that the improved lens can handle beams which are wider in the X-direction too, not only in the direction at right angles.

The correcting effect can be understood from the fact that in the XY-plane the curved reversing lens acts approximately like a convex cylindrical mirror. It is known that the cylindrical aberration of convex mirrors is negative, that is to say parallel beams falling on it at increasing angles to the normal leave it with increasing divergence. This is true also of a lens according to this invention as has been confirmed by accurate graphical ray tracing, and also by direct experiments on reversing lenses as in Figs. 7 and 8. Consequently the overconvergence imposed on the beam by the X-deflection, due to deflection focusing is partly compensated by the divergence introduced by the reversing lens. Full compensation is also possible, if the distance Z (the distance of the deflection centre from the repeller) is made appreciably larger relative to the curvature radii R_1 etc., of the lens than in the case shown in Fig. 7. One can, however, achieve full compensation or even overcompensation at any Z/R ratio, by curving the lens, or at least the negative trough 15, not into a circular arc but into a curve with a curvature increasing from the centre outwards, for example according to a fourth order law. Calculations show that full compensation can be achieved with a deviation from the circular shape which would only just be visible on the scale of Fig. 7.

The actual deflection astigmatism introduced by the X-deflection plates 16 can, of course, be influenced by the choice of the deflection system. With the parallel-field deflection system shown in Figs. 7 and 8 the deflection astigmatism or over-focussing is only in the X direction, but is relatively severe, that is to say, the locus of the X focus is strongly curved. If, however, the plates 16 were replaced by deep channel-shaped deflection electrodes, the astigmatism in the X direction would be reduced. However, a similar aberration, but of opposite sign, would be introduced in the Y direction. That is to say, the beam would not focus in either the X direction or the Y direction at all points in a straight line, but the locus of the focus obtained in the X direction would be curved in one direction and the locus of the focus in the Y direction would be oppositely curved, so that focussing would not be achieved simultaneously in both the X and Y directions except in the centre of the sweep, that is in the absence of any deflection field. In Fig. 9 a system of deflection electrodes which achieves a useful compromise between these two situations is shown in perspective. It comprises two deflection plates 16' 16'' which are of shallow channel cross-section, and lying across the two

open sides of the electrode system thus formed, and suitably spaced therefrom are two further plate electrodes 17' 17''. These plates 17' 17'' are maintained at the mean potential of the X deflection waveform. The effect then is that the beam is, as shown diagrammatically in the drawing, focussed simultaneously in both the X direction and in the Y direction at all angles of deflection, but the locus of the focus is less curved than in the case of the simple plate system of Figs. 7 and 8. Indeed, the locus is only half as strongly curved as in the parallel-field system. The use of such a deflection system enables the reversing lens according to the invention to be designed readily so as to eliminate the residual deflection astigmatism, without 4th order correction of the repeller profile.

In the design of the curved reversing lens according to the invention great care must be taken to ensure that a plane fan of rays entering it is reversed into a plane and not into a conical surface. It has been found that the shape of the said ray surface is appreciably influenced by the radius R_2 of the spine, though at given R_2 it is little influenced by the gap G_1 , that is to say by the spacing of the spine from the repeller bottom. It is found that with decreasing R_2 the cone of emergent rays becomes concave towards the central plane, whereas with increasing R_2 it becomes convex. It is plane at a certain R_2 at which the spine is curved concentric to or slightly more sharply than concentric to the repeller bottom.

The curvature of said ray surface is also strongly influenced by the curvature radii R_3 and R_4 which determine the outer gap between the electrodes. It was found that it is convenient to keep G_2 also uniform so that the remaining variable is the curvature of the outer gap, as a whole, if R_1 and Z are considered as given. It was found that for $Z/R_1=0.7 \div 1.0$ the best plane ray surface was obtained with a completely coaxial arrangement of the electrodes

$$R_3 - R_1 = H = 0.725 \text{ A}$$

that is to say with the cross section as shown in Fig. 6 and in Fig. 8, rotated around an axis. If the curvature of the outer gap is made less than corresponding to coaxiality, the ray surface is a cone concave towards the symmetry plane of the lens; if the curvature is stronger, it becomes convex, that is to say it turns outwards. To a smaller extent the said curvature can be regulated by the gap G_2 , and this has the advantage that thereby a fine adjustment can be made without altering the shape of any of the electrodes. If the cone is concave towards the symmetry plane it can be a little flattened by reducing the gap G_2 and vice versa. This, however, should be used only for small adjustments, as the beam quality deteriorates if G_2 departs appreciably from its previously stated optimum value.

A further correction which may be applied to the lens is for compensating an effect which has been observed in the model as described, namely that the spacing A between the incident and emergent axes decreases somewhat towards the ends, and the lens, though telescopic for $d=0$, is not telescopic but convergent for larger deflection angles. This effect can be corrected by thickening the spine electrode 14 at its ends as shown in perspective in Fig. 10. In the example described the axis spacing varied from $A=1.0$ at the centre, to $A=0.96$ for a deflection angle $\alpha_1=0.1$ radian and to $A=0.92$ for $\alpha_1=0.14$ radian. This may be corrected by making the thickness of the centre spine electrode increase from $w=0.3$ A at the centre to $w=0.6$ A at each end, the increase in thickness being effected according to a parabolic law. The correct thickening for the spine may be achieved by shaping the two sides of the spine as conical surfaces of the appropriate radius and cone angle.

A second method for compensating the said reduction of the spacing A with increasing deflection angle consists in increasing the width W_1 of the repeller trough with the deflection angle α , according to a parabolic law, for

instance from 2.0 in the centre to 2.05 where it is intersected by the ray deflected at $\alpha=0.1$ radian, to 2.1 at $\alpha=0.14$, and 2.2 at $\alpha=0.2$. The repeller trough thus modified acquires, seen from above, a shape roughly resembling that of a violin, as shown in perspective in Fig. 11. Both methods, that is to say thickening the spine towards the ends and widening the repeller trough, may be of course combined with advantage in order to keep a rigorously constant and independent of deflection angle, and to ensure that the lens is telescopic at all deflection angles.

As examples of lenses according to the invention the following table gives the relative dimensions of two designs which have given satisfactory results in terms of deflection sensitivity and freedom from aberrations, the dimensions being given in terms of the spacing between the incident and emergent axes as above stated:

	Lens A	Lens B
W (Outer width of repeller trough)	2.5	2.34
W ₁ (Inner width of repeller trough)	2.1	1.98-2.2
W ₂ (Inner spacing between outer positive electrode)	1.75	1.66
H (Height of repeller in the central cross section)	0.725	0.72
G ₁ (Gap between repeller and spine)	0.51	0.4
G ₂ (Gap between repeller and pos. side electrode)	0.525	0.4
w (Thickness of spine)	0.31	0.3-0.6
r ₁ (Radius of repeller profile)	0.3	0.3
r ₂ (Radius of repeller edge)	0.1	0.1
r ₃ (Radius of pos. flanking electrodes profile)	0.2	0.1
R ₁ (Radius of repeller bottom)	8.0	5.67
R ₂ (Radius of spine edge)	8.65	6.1
R ₃ (Radius of repeller edge)	8.725	6.4
R ₄ (Radius of positive flanking electrode)	9.25	6.9
Z (Deflection centre to repeller trough)	7	6.6
z (Distance of reversing line from rep. bottom measured)	1.1	0.75

Though in these designs all data have been related to the interplane distance A, it is understood that it is not necessary to scale up all dimensions when passing from one system to a larger one. It is possible, without large errors, to keep the cross section constant, and to scale up only the curvature radii R₁ and the distance Z. The reason for this is that the electron motion as projected on the plane XY, as in Fig. 7, is in first approximation independent of the motion at right angles thereto, as shown in Fig. 6. Such an incomplete scaling-up will of course necessitate small adjustments in order to give a perfectly plane ray-surface.

No excessive accuracy is required in the manufacture of the electrodes of the reversing lens, which can be made by pressing, swaging or spinning from sheet metal, or by electro-forming. High-permeability soft nickel-alloys are preferable, as these act at the same time as magnetic screens.

I claim:

1. Electron lens for receiving an incident electron beam deflectable in an incidence plane and reversing it upon itself so as to return it in an emergence plane parallel to said incidence plane and spaced therefrom comprising a trough-shaped repeller electrode presenting its open side towards the incident beam and spanning the space between said incidence and emergence planes with its side walls lying outside the respective planes, a spine electrode in the form of a wall lying between said incidence and emergence planes and having an edge lying in the mouth of said trough-shaped repeller electrode, and two flanking electrodes each in the form of a wall and located one on each side of said spine electrode outside the respective incidence or emergence plane, the base of said repeller electrode and the edges of its side walls all being curved in a sense convex towards the direction of incidence, and the edges of said spine electrode and said flanking electrodes all being curved so as to define parallel gaps between the base of the repeller electrode and edge of the spine electrode and between the edges of the side walls of the repeller electrode and of the flanking electrodes respectively.

2. Electron lens as claimed in claim 1 wherein the curvature of the base and edges of the side walls of said repeller electrode and the edges of said spine and flanking electrodes to the enumerated parts increases progressively from the centre towards each end of the lens.

3. Electron lens as claimed in claim 2 wherein the increase in curvature follows a fourth-order law.

4. Electron lens as claimed in claim 2 wherein the spine electrode increases in thickness from its centre towards each end thereof.

5. Electron lens as claimed in claim 4 wherein the increase in thickness of the spine electrode follows a parabolic law.

6. Electron lens, adapted to operate in conjunction with an electron gun and a beam deflection system, having two symmetry planes at right angles to one another, the first of said planes being parallel to the plane fan of electron beams produced by said deflection system, while the second plane passes through the gun axis and through

20 the mid-plane of the deflector system, comprising a trough-shaped repeller electrode of U-like cross section in planes parallel to the second-named symmetry plane, operative at a low potential near that of the gun cathode, a substantially plane, profiled central spine electrode centered in the first-named symmetry plane, and two substantially plane, profiled side electrodes, flanking said central electrode, the three last-named electrodes being operative at a high potential near the total accelerating voltage of the electron beam, all four electrodes having

25 profiles in planes parallel to the first-named symmetry plane convex to the side from which the electron beam is incident, whereby the plane fan of the incident beams is converted into another plane fan of emerging beams, parallel to the first plane fan and symmetrical thereto

30 relative to the first-named symmetry plane of the lens.

7. Electron lens as claimed in claim 6, in which the profiles of the spine and flanking electrodes and the profile in which the first-named symmetry plane intersects the repeller electrode are all substantially co-axial and

35 consequently approximately equidistant along their length.

8. Electron lens as claimed in claim 6, in which the width between the flanks of the U-shaped repeller trough increases according to an approximately parabolic law with the distance from the second-named of the symmetry planes.

9. Electron lens as claimed in claim 6, in which the thickness of the spine electrode, at least on its portion facing the bottom of the repeller electrode, increases according to an approximately parabolic law with the distance from the second-named of the symmetry planes.

10. Electron lens adapted to receive an incident electron beam deflectable in an incidence plane and return it in an emergence plane parallel to said incidence plane comprising a central spine electrode, a pair of flanking electrodes parallel to and disposed on opposite sides of said spine electrode in spaced relation thereto, the spaces between said flanking electrodes and said spine electrode defining incidence and emergence apertures, respectively, and a repeller electrode spaced from said spine and flanking electrodes and spanning said incidence and emergence apertures.

11. Electron lens as claimed in claim 10 wherein all of said spine and flanking electrodes are maintained at substantially the same positive potential and said repeller electrode is maintained at a negative potential.

12. Electron lens as claimed in claim 10 wherein said spine electrode defines a plane of symmetry of said lens, and said repeller electrode and the edges of said spine and flanking electrodes presented towards said repeller electrode are all curved in planes parallel to said plane of symmetry.

13. Deflection system for an electron discharge device comprising primary deflection means adapted to produce deflection of a cathode ray beam in an incidence

11

plane, and an electron lens adapted to receive an incident electron beam in said incidence plane and return it in an emergence plane parallel to said incidence plane, said primary deflection means comprising a pair of deflecting electrodes of channel cross section with the open sides of the channels facing one another across a gap and a pair of plate electrodes lying across but spaced from said gap, said electron lens comprising a repeller electrode, a central spine electrode presenting an edge towards said repeller electrode, and two flanking electrodes substantially parallel to and disposed on opposite sides of said spine electrode in spaced relation thereto and presenting respective edges towards the edges of said repeller electrode, the gaps between the repeller electrode and the edge of said spine electrode presented thereto and between the edges of said repeller electrode and the edges of said flanking electrodes presented thereto all being curved in planes parallel to said incidence and emergence planes.

12

14. Deflection system as claimed in claim 13, wherein said plate electrodes are maintained at the mean potential of said deflecting electrodes, and the gap between said deflecting electrodes is so dimensioned as to produce substantially equal deflection focusing in said incidence plane and in planes at right angles thereto.

UNITED STATES PATENT OFFICE
CERTIFICATE OF CORRECTION

Patent No. 2,926,274

February 23, 1960

Dennis Gabor

It is hereby certified that error appears in the printed specification of the above numbered patent requiring correction and that the said Letters Patent should read as corrected below.

Column 1, line 45, for "objection" read -- object --; column 4, line 39, after "13.", beginning with "The electron lens" and ending with "optical axis." in line 56, same column, should appear as a new paragraph instead of as in the patent; line 49, for "electode" read -- electrode --; column 6, line 11, for "abberation" read -- aberration --; line 69, for "re" read -- are --; column 9, in the table, column 1 thereof, fourth line from the bottom, for "postive" read -- positive --; column 10, line 4, after "electrodes" strike out "to the enumerated parts".

Signed and sealed this 9th day of August 1960.
